ENDOSCOPE AND OBTURATOR THEREFOR

Joseph E. Held, New York, N. Y., assignor to
American Cystoscope Makers, Inc., New York,
N. Y., a corporation of New York

Application January 31, 1946, Serial No. 644,557

4 Claims. (Cl. 128—4)

1

The instant invention pertains generally to surgical instruments, and more particularly to endoscopic instruments adapted to be inserted into body cavities for the purpose of examining, treating and/or carrying out surgical operations within such cavities. In one of its more specific aspects, the invention relates to a multiple-fenestra endoscopic instrument and an obturator for such an instrument to prevent the fenestras from damaging body tissue in the course of inserting the instrument in a cavity.

It is the primary object of this invention to provide an instrument of the character indicated that is capable of performing its intended functions in an effective and trouble-free manner.

Another object of the invention is to provide an endoscopic instrument, having a plurality of fenestras, that may be readily inserted into a body passage without damage to body tissue with which it may come in contact during such insertion.

Another object of the invention is to provide an improved obturator that may be readily inserted into and subsequently withdrawn from a multiple-fenestra endoscope.

A further object of the invention is to provide an obturator for multiple-fenestra endoscopes, which obturator is relatively simple and compact in design and dependable in operation.

With the above and other objects in view, the invention comprises the devices, combinations and arrangements of parts set forth in the following detailed description and illustrated in the annexed drawing of a preferred embodiment of the invention, from which the several features of the invention, together with the advantages attainable thereby, will be readily understood by persons skilled in the art.

In the drawing:

Figure 1 is a side elevational view of an endoscopic instrument embodying the devices of this invention, and illustrating the obturator in operative association with the fenestras of the instrument;

Figure 2 is a side elevational view of an obturator constructed in accordance with this invention;

Figure 3 is a vertical cross-sectional view of a forward portion of the instrument shown in Figure 1;

Figure 4 corresponds to Figure 3, and illustrates the obturator out of operative association with the fenestras of the endoscopic instrument;

Figure 5 is a cross-sectional view taken along line 5—5 of Figure 3;

Figure 6 is a cross-sectional view taken along line 6—6 of Figure 4;

Figure 7 is a view of the left end portion of the obturator shown in Figure 2, rotated 180° vertically and horizontally;

Figure 8 is a cross-sectional view taken along line 8—8 of Figure 2; and

Figure 9 is a top plan view of the forward portion of Figure 2.

10 Referring now to the drawing, wherein like reference numerals are employed to denote corresponding parts throughout the several views, and more particularly to Figure 1, I have depicted an endoscopic tube 10 having a plurality of fenestras 11 and 12 formed therein and spaced therearound. These fenestras are preferably arranged opposite each other. Secured to the forward end of tube 10 is an extension generally indicated by numeral 13 and including a first unit 14 having a ball head or end 15 that engages the rearward end of a second unit or beak 16 to form a swivel or ball and socket connection therewith. The free end of beak 16 is rounded, as at 17, to facilitate insertion of the instrument in a body passage. Intermediate the fenestrated portions of tube 10 and extension 13 is a lamp mounting 18 that carries a lamp 19 adapted to transmit light rays through both of the fenestras to the exterior of tube 10 simultaneously. Adjacent lamp 19 is a perforate partition 20 disposed across the interior of tube 10. Partition 20 protects lamp 19 from being damaged by instruments inserted into the tube through its rearward end and additionally, as will be explained further along herein, serves as a stop to limit relative movement in one direction between tube 10 and the obturator of this invention.

40 An electrical terminal 25 is adapted to be connected to a suitable source of electricity (not shown) and includes a pair of legs 26 and 27 having integral arcuate spring contact elements 28 and 29, respectively, that ride in corresponding spool-like elements 30 and 31 for energizing lamp 19 in a manner well-known to the art.

45 Affixed to tube 10 is a collar 32 having a pair of conduits, one of which is indicated at 33 in Figure 1, for transmitting and withdrawing irrigating liquid into and from a body passage by way of the interior of tube 10. A sleeve 34 is secured to and rotatable about the axis of tube 10 and is provided with a detent means 35 for controlling the relative angular position thereof with respect to the tube. Suitably coupled to the rearward end of sleeve 34 and rotatable therewith 50 is a locking unit 36 that has a laterally extending

actuating handle 37, and that is preferably the same as or similar to the locking mechanism disclosed in Reinhold H. Wappler Patent No. 1,880,551 granted October 4, 1932, to which reference may be had for details of construction.

Turning next to Figure 2, an obturator assembly, designated by numeral 40 illustrated therein, includes a hollow obturator head 41 longitudinally slotted at 42 and 43 (Figures 2 and 7) to obtain a web 44 and a pair of laterally extending substantially parallel members 45 and 46, having rounded or camming end surfaces 45' and 46', respectively, as is best shown in Figures 4 and 8. Member 45 has a teat or stop lug 47 formed integral therewith and projecting into slot 42. It will be observed that obturator head 41 is generally U-shaped in longitudinal cross section, and further that the outer face of each member 45 and 46, that merges with web 44, tapers forwardly. Obturator head 41 is preferably made of a suitable resilient metal to permit ready outward deflection of members 45 and 46 with respect to each other upon the application of a force tending to produce such deflection.

The forward end of a control rod 50 is disposed within obturator head 41 and is axially movable intermediate and along members 45 and 46. Rod 50 has a blind bore 51 for the reception of a portion of a compression spring 52 disposed wholly within obturator head 41 and bearing against the inner face of web 44 and the blind end of bore 51 to normally and yieldingly move head 41 toward the left with respect to rod 50, as viewed in Figure 2. Integral with rod 50 and extending forwardly thereof is a stop arm 53 that rides in slot 43 and that abuts the inner face of web 44 to limit movement of obturator head 41 toward the right with respect to rod 50, as viewed in Figure 8. A stop pin 54 carried by rod 50 rides in slot 42 and bears against stop lug 47 to limit movement of obturator head 41 toward the left with respect to rod 50, as viewed in Figure 2, this being the normal relative position of obturator head 41 and rod 50.

Rod 50 carries a double frusto-conical element 55 having a forwardly tapering face 56 for imparting outward deflection to members 45 and 46 under certain conditions, as will be discussed further along. At the rearward end of rod 50 is a handle 57 having a forwardly tapered portion 58 that carries a pair of locking pins 59, one of which is shown in Figure 2.

The normal relative position of the devices constituting obturator assembly 40 is as shown in Figure 2, that is to say, obturator head 41 is normally at its extreme protracted position with respect to control rod 50 due to the action of spring 52, and as allowed by stop lug 47 and stop pin 54. Under these conditions, element 55 is out of engagement with the free ends of members 45 and 46. The obturator assembly is insertable in endoscopic tube 10 and movable forwardly therewith, the parts of the obturator assembly remaining in the relative position shown in Figure 2 until web 44 abuts the rearward face of partition 20. Upon continued movement of control rod 50 toward the left, further forward movement of obturator head 41 is prevented by partition 20, but the forward end of rod 50 is protracted into the obturator head against the action of compression spring 52, thereby bringing tapered face 56 of element 55 into engagement with camming surfaces 45' and 46' of members 45 and 46, respectively, and effecting

outward deflection of members 45 and 46 to bring these members into registration with corresponding fenestras 11 and 12 (Figures 1 and 3). At such time, tapered surface 58 of handle 57 forms a snug fluid-tight connection with sleeve 34 and the parts are maintained in the assembled position shown in Figure 1 through the engagement of locking pins 59 by locking unit 36, as is taught in the above-mentioned Patent No. 1,880,551.

The instrument shown in Figure 1 may then be inserted in a body passage in the usual manner. After the fenestras have been disposed in the desired region of a body cavity, locking unit 36 is manipulated to release locking pins 59. Initial withdrawal of control rod 50 effects partial retraction of the forward portion of this rod with respect to obturator head 41 and disengagement between element 55 and the free ends of members 45 and 46, thereby permitting these members to return to their normal relative position and out of registration with their corresponding fenestras. Continued withdrawal of control rod 50 results in full retraction of the control rod with respect to obturator head 41 until the parts assume the relative position shown in Figure 4, whereupon the entire obturator assembly may be completely withdrawn from endoscopic tube 10.

From the foregoing, it is believed that the construction, operation, and advantages of my present invention will be readily comprehended by persons skilled in the art. It is to be clearly understood, however, that various changes in the apparatus set forth above may be made without departing from the scope of the invention, it being intended that all matter contained in the description or shown in the drawing shall be interpreted as illustrative only and not in a limiting sense.

I claim:

1. In an instrument of the character described, an endoscopic tube having a plurality of fenestras formed therein and spaced therearound, an obturator head insertable into said tube to the region of said fenestras and comprising a web and a plurality of spaced members projecting laterally of said web, a rod extending into said head and movable along said members, and means carried by said rod for urging said members outwardly with respect to each other upon predetermined movement of said rod with respect to said head in one direction to effect registration between each of said members and a corresponding fenestra.

2. In an instrument of the character described, an endoscopic tube having a plurality of fenestras formed therein and spaced therearound, a unitary obturator head insertable into said tube to the region of said fenestras and comprising a web and a plurality of spaced substantially parallel members projecting laterally of said web, a rod extending into said head and movable along said members, means carried by said rod for substantially simultaneously engaging the free end of each member and imparting outward deflection to said members with respect to each other upon predetermined movement of said rod with respect to said head in one direction to effect registration between each of said members and a corresponding fenestra, and means normally urging said rod in the opposite direction with respect to said head to effect disengagement between said first mentioned means and said members.

3. In an obturator for an endoscopic instrument that includes an endoscopic tube having a

plurality of fenestras formed therearound, a head that is generally U-shaped in cross section and adapted to be inserted into said endoscopic tube to the region of said fenestras, said head including a web and a pair of substantially parallel spaced members, a rod movable along said head intermediate said members, means for normally and yieldingly maintaining said head in a predetermined position with respect to said rod, and means carried by said rod for substantially simultaneously imparting outward deflection to each of said members with respect to the other member upon predetermined movement of said rod with respect to said head against the action of said last mentioned means.

4. In an obturator for an endoscopic instrument that includes an endoscopic tube having a plurality of fenestras formed therearound, a head that is generally U-shaped in cross section and adapted to be inserted into said endoscopic tube to the region of said fenestras, said head in-

cluding a web and a pair of substantially parallel spaced members, a rod movable along said head intermediate said members, means for normally and yieldingly maintaining said head in a predetermined position with respect to said rod, and wedge means carried by said rod for substantially simultaneously imparting outward deflection to each of said members with respect to the other member upon predetermined movement of said rod with respect to said head against the action of said last mentioned means.
